Salathiel Ellis assignor to John G. Wellswood
City of New York, Letters Patent No. 23, dated September
24, 1844, antedated August 12, 1844. —

The date referred to in these Letters Patent and
making part of the same. —

To all whom it may concern:

Be it known that I, Salathiel Ellis of the City of
New York, have designed and executed or moulded a
Medallion Portrait bust of Theodore Frelinghuysen,
in mezzo-relief, and I do hereby declare that the
following is a full and exact description of the method
of making the said Medallion bust — I first take the
exact outline of the profile and bust by a reducing
machine, drawing out the features by pencil, then
proceed in the usual manner to model the same
in clay, from which a mould is made from any
suitable material, in which the medallion busts are
cast, out of any suitable material.

Now what I claim as my design and production
and which I desire to secure by letters patent, is
the moulding and casting in mezzo-relief from
any suitable material, the particular portrait bust
of Theodore Frelinghuysen, in medallion form
of any size, according to the design shown in the
drawing hereto attached (the same being a copy
of specimen sent).
